United States Patent

Des. 240,614
Patented July 20, 1976

240,614

REFUSE CAN STORAGE UNIT

Samuel Paterno, Des Moines, Iowa, assignor to Paterno Enterprises, Des Moines, Iowa

Filed Jan. 29, 1975, Ser. No. 544,938

Term of patent 14 years

Int. Cl. D12—02

U.S. Cl. D12—33

FIG. 1 is a frontal perspective view of a refuse can storage unit showing my new design;

FIG. 2 is a top plan view thereof;

FIG. 3 is an end elevational view thereof as seen from the right-hand end of FIG. 1;

FIG. 4 is a rear elevational view thereof;

FIG. 5 is a front elevational view thereof; and

FIG. 6 is an end elevational view thereof opposite to that of FIG. 3.

I claim:

The ornamental design for a refuse can storage unit, substantially as shown and described.
